UNITED STATES PATENT OFFICE.

JOSEPH WM. STORER, OF NEW YORK, N. Y.

VARIABLE CONDENSER.

Application filed November 5, 1925. Serial No. 66,992.

This invention relates to variable condensers, and more especially to the class wherein a frame supports a plurality of stator plates and a corresponding rotor unit is mounted on a carriage pivoted to the stator frame, while a pair of links connect the rotor and the rotor carriage with a crank mounted on a control dial shaft.

The main object of my invention is to provide a variable condenser which has extreme ranges of capacity, and moreover, which is of simple, efficient and inexpensive construction.

In the accompanying drawing forming part of this specification:—

Fig. 1 is a perspective view of an apparatus embodying the novel features of my invention.

Fig. 2 is a side view of the same apparatus when the rotor has been partly raised.

Fig. 3 is a similar view when the parts are in extreme raised position.

Fig. 4 is a view of a stator plate and a rotor plate as relatively spaced when the condenser occupies the position of Fig. 3.

In the art of controlling radiant energy, it is often desirable to condensers which have very extreme ranges of capacity, that is, which have great capacity in one normal position of the parts, and a very low capacity value at the extreme opposite position of the same parts. This necessitates in the last position, a very great spacing between the stator and rotor plates. In order to accomplish this, the present invention is designed. Incidentally, several advantages will become apparent as this specification proceeds.

In the practice of my invention, a pair of frame sides 1 and 2, made of any rigid material such as metal or bakelite are fastened together by means of three tie rods 16, 17 and 18, and a group of stator plates 13, 13 clamped in spaced relation therebetween. Each of the stator plates has a set of lugs 22, 23 and 24 which correspond with the tie rods 16, 17 and 18, respectively. Upon the mentioned frame side 1, is secured a bearing 10 for the dial shaft 8, the latter being provided with a knob 15 whereby to turn it.

The rotor shaft 25 is provided with a plurality of plates indicated by 14, and is mounted in a rocking carriage consisting of a pair of strips 4 and 11 which are pivoted on frame sides 1 and 2 as indicated at 20. A heavy cross

bar 12 serves to counterbalance the weight of the rotor unit and also to unite the strips 4 and 11 of the carriage structure.

The means for moving the rotor about its shaft consist of a crank 9 is secured to shaft 8 and a corresponding crank 5 secured to shaft 25, while a link 6 is connected to crank 5 and at 19 to crank 9. In order to increase the raising action for the rotor, the link 7 is secured to the rotor carriage at 3 and at 19 to the mentioned crank 9. Both links are thus connected to the same crank on dial shaft 8, and their action is therefore simultaneous upon rotation of this shaft.

In the low position of the rotor plates, as seen in Fig. 1, it will be noted that link 6 partly envelopes shaft 8, and, by virtue of its connection to crank 9, the shaft cannot be turned further in a counter-clockwise direction. The link in this manner acts as a stop at this extreme position of the rotor, and the condenser has its maximum capacity.

If the knob 15 is rotated slightly clockwise, link 7 will raise the carriage, while link 6 will hold back the crank 5 so that the rotor will occupy a nearly vertical position as seen in Fig. 2. Continuing the rotation as far as possible, until the parts assume the positions seen in Fig. 3, the projection 21 on link 6 will abut shaft 8 and prevent any further rotation of the knob. As the carriage has now been raised to its highest possible angle, and the rotor also turned to its highest position, the rotor and stator plates are in the relatively spaced position shown in plan view in Fig. 4. The great space between the plates here evident makes for an exceedingly low capacity, especially as there is not even a parallelism in the relation of the rotor plates to the stator plates. As may be seen in Fig. 4, the stator plates have a clearance 26 for the rotor shaft 25, so that the two units of plates will never be in contact.

The rotor shaft may, of course, be equipped with the usual dial as well as the knob, and the whole mounted in a cabinet by any known means, the whole range of possible positions of rotor between the extremes herein shown providing a very great variety of different capacities. The shape of the plates also enhance the value of my invention in that they are more than semicircular in form, thus containing more active surface than usual with a given radius.

Having now fully described my invention, I claim:

1. A control device comprising a frame, a rigid member secured thereon, a rotatable shaft upon said frame having a crank, a rocking carriage mounted on said frame and pivoted thereto intermediate the extremities of the carriage, a second shaft on said carriage having a crank, a link connected to said first crank and to said second crank, and a second link connected to said carriage and to said first crank.
2. A control device comprising a rigid member, a rocking member pivotally mounted thereon, a rotary shaft also mounted on said frame and provided with a crank secured thereto, a second shaft mounted on said rocking member in spaced relation to the pivotal mounting thereof on said rigid member, a crank on said second shaft, a link connecting both said cranks, and a second link connected to said first crank and said rocking member and adapted to partially surround said first shaft in one extreme position.
3. A control device comprising a rigid member, a rocking frame pivotally mounted thereon, a shaft supported by said rigid member having a crank thereon, a second shaft mounted on said frame in spaced relation to the pivotal mounting thereof on the first member, a rotary member secured on said second shaft and a crank also secured thereon, a link connecting said first crank with the second crank, and a second link pivotally connected at one extremity to said rocking frame and at the other to said first crank, and a projection on said last link adapted to engage said first shaft in extreme advanced position of movement to provide a stop, said last link being adapted to partially surround and engage the same shaft in the other extreme position, and means to rotate said shaft.
4. A control device including the combination with a fixed member, of a rotatable shaft supported in association therewith having a crank thereon, a rocking frame pivoted on said fixed member in such manner as to partly envelop the same, a second shaft mounted on one end of said frame having an operative member fixed thereon to rotate therewith, said frame being rockable to raise said second shaft and operative member above said fixed member, a crank on said second shaft, a link connecting said two cranks to cause said operative member to be turned from operative relation with respect to said fixed member simultaneously with the raising thereof by said frame, and means to rock said frame from said first shaft.
5. A control member including the combination with a fixed member, of a rockable frame pivotally mounted in association with said fixed member and having an end counterbalance, a shaft borne upon the opposite end of said frame and having an operative member secured thereon which is both swingable away from the first fixed member upon rocking of said frame and further separable therefrom by rotation with said shaft, means associated with said fixed member for rocking said frame and means for simultaneously controlling rotation of said operative member in positive manner in synchronism with rocking movement of said frame.
6. A control device including a fixed member, a forked frame pivotally mounted exteriorly upon said fixed member and provided with a shaft upon its furcated ends, an operative member secured upon said shaft so as to be swingable by said frame from proximate relation to said fixed member, a manually rotatable shaft supported upon said fixed member, a positive connection between said manual shaft and said first shaft to provide simultaneous rotation of the manual shaft and said operative member and increase the space relation between the same and the fixed member, and a second connection between said manual shaft and said frame for directly rocking the same upon rotation of said manual shaft.
7. A control device including the combination with a rigid frame and a fixed member thereon, of a rocking carriage pivoted on said frame, a shaft mounted on said carriage in spaced relation to the pivotal mounting thereof, an operative member secured on said shaft corresponding with said first fixed member and being rotatable with said shaft, a manually rotatable shaft supported on said first frame in spaced relation to said pivotal mounting of said rocking carriage, a crank on each of said shafts, a link connecting said cranks and having such a contour as to form extreme stops against said manual shaft to determine the two extreme rotated positions of said operative member in which it is relatively proximate to, and spaced from, said fixed member, and a link also connected to the crank on said manual shaft and to said rocking carriage to one side of the pivotal mounting thereof in order to provide further spacing of said operative member away from said first fixed member at will.

In testimony whereof, I have signed my name to this specification this second day of November, 1925.

JOSEPH WM. STORER.
